UNITED STATES PATENT OFFICE.

LOUIS B. GOLDBERG, NATHAN GOLDBERG, WILLIAM GOLDBERG, AND JACOB M. GOLDBERG, OF DENVER, COLORADO.

CAMP-STOVE CASING.

Application filed April 7, 1924. Serial No. 704,691.

To all whom it may concern:

Be it known that we, LOUIS B. GOLDBERG, NATHAN GOLDBERG, WILLIAM GOLDBERG, and JACOB M. GOLDBERG, citizens of the United States, residing at Denver, in the county of Denver and State of Colorado, have invented certain new and useful Improvements in Camp-Stove Casings; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in camp stove casings and has special reference to a modification of the type of casing disclosed and claimed in our co-pending application, Serial No. 693,790, filed February 19, 1924.

Camp stoves of the type to which this invention relates employ gasoline as fuel. The fuel is contained in a gas-tight cylinder to which a rigid pipe, termed a generator, is connected. When the stove is packed for transportation the fuel container is preferably placed within the walls of the casing. The generator projects through the end of the casing and extends along the outside thereof. Owing to the fact that these stoves are subjected to rough usage, we find that the generator needs to be protected from injury when the stove is not in use. We have therefore provided a suitable protecting cover that is secured to one of the stove supports and adapted to be swung into position against the end of the casing for the purpose of enclosing the generator.

Our invention can be most clearly described and will be most readily understood when reference is had to the accompanying drawing in which the preferred embodiment of our invention is illustrated, and in which:

Fig. 1 is a perspective view of one end of the stove casing showing the generator cover in closed position, parts being broken away to better disclose the construction;

Fig. 2 is an end view of the casing with the cover in closed position; and

Fig. 3 is a fragmentary side elevation showing the cover in inoperative position.

The casing has a bottom 1, side walls 2,

end walls 3 and a hinged lid 4. One end wall 3 is provided with a notch 5 extending downwardly from the upper edge, in the manner shown in Figs. 1 and 2. Each end of the casing is provided with a support 6 consisting of a round bar having a straight portion 6. The ends of the straight portion are bent at right angles thereto and into two angularly related parts 7 and 8, connected by a U-shaped portion 9. The extreme end 10 of each part 8 is bent at right angles to the plane in which the parts 7 and 8 lie, and engage in suitable openings in the sides 3. The support described can be swung about the axes of ends 10 into the position shown in Figs. 1 and 2 and into the position shown in Fig. 3. Secured to the straight portion 6 is a housing or cover formed from a piece of sheet metal having one portion 11 of curved, substantially semi-circular cross-section. One edge of part 11 is formed into a flat flange 12, while the other edge 13 is rolled around the straight portion 6. The connection between the cover and the straight portion 6 is loose so that the cover may rotate on the part 6. The ends of the cover may be closed by means of end pieces 14, although this is not necessary. The flange 12 has two openings 15 for the reception of the turn buttons 16 whose function will hereinafter appear. The support and the cover attached thereto may be swung into the position shown in Figs. 1 and 2, in which position the concave side of the part 11 will fit against the outside of the end wall 3 and form a semi-cylindrical chamber. The turn buttons 16 serve to hold the cover in operative position. Within the casing we place the fuel container 17 that is connected to the generator tube 18 by means of a short piece of pipe 19 which extends through the notch 5. A valve 20 controls the flow of fuel from the container 17 to the generator 18 and has a knurled head 21 on the end of the rotatable valve stem. It is apparent that when the parts are in the position shown in Fig. 1, the generator 18 will be protected by the cover 11. When the stove is to be used, the parts are moved into the inoperative position shown in Fig. 3. The lid 4 has a flange portion 22 that projects downwardly a sufficient distance to form a stop for the rolled portion 13, in the manner shown in Fig. 1. The lid is secured

in place by means of hinges 23 and held in place by means of catches 24.

From the above, it will be apparent that we have produced a camp stove casing that is constructed in such a manner that when the fuel container 17 is in place within the same, the generator 18 lies on the outside of the casing parallel to one end thereof. The housing or cover 11 can be moved into operative position against the end of the casing where it will form a protective housing for the generator. When the stove is in use, the support and cover can be moved to the position shown in Fig. 3.

15. Having now described our invention, what we claim as new is:

1. A stove casing having a bottom, two sides and two ends, a support pivotally connected to the sides near one end of the casing, a cover member connected to said support, said cover member being adapted to be moved into operative position against the end member, and means for holding the cover in operative position.

25. 2. A vapor stove casing having a bottom, two side walls and two end walls, one of said end walls having a notch in its upper edge, a support pivotally attached to the sides near the end having the notched end wall, said support having a straight portion adapted to be swung against the bottom of the casing, a cover member hingedly connected to the straight portion of the support, said cover being of curved cross-section and adapted to be moved into position against the end of the casing and into a similar position against the bottom thereof.

30. 3. In a portable camp stove, in combination, a casing having a bottom, two side walls and two end walls, a support pivotally connected to the sides of the casing near one end thereof, said support having a straight portion adapted to be swung about the pivots into contact with the bottom or the end, a cover pivotally connected to the straight portion, said cover having a portion of curved cross-section with a straight flange secured along one edge, said cover being adapted to be moved into operative position against the end with the concave portion innermost, and means cooperating with the flange for holding the parts in operative position.

45. 4. A stove casing adapted to receive a fuel tank having a generator tube attached thereto, the tank being within the casing and the generator tube on the outside thereof, said casing having a bottom, two sides and two ends, a support pivotally connected to the sides near one end of the casing, a cover member connected to said support, said cover member being adapted to be moved into operative position against the end member for enclosing the generator tube, and means for holding the cover in operative position.

60. 5. A vapor stove casing adapted to receive a fuel tank having a generator tube attached thereto, the tank being within the casing and the generator tube on the outside thereof, said casing having a bottom, two sides and two ends, a support pivotally connected to the sides near one end of the casing, a cover member connected to said support, said cover member being adapted to be moved into operative position against the end member for enclosing the generator tube, and means for holding the cover in operative position.

65. 6. A vapor stove casing adapted to receive a fuel tank having a generator tube attached thereto, the tank being within the casing and the generator tube on the outside thereof, said casing having a bottom, two side walls and two end walls, one of said end walls having a notch in its upper edge, a support pivotally attached to the sides near the end having the notched end wall, said support having a straight portion adapted to be swung against the bottom of the casing, a cover member hingedly connected to the straight portion of the support, said cover being of curved cross-section and adapted to be moved into position against the end of the casing for enclosing the generator tube and into a similar position against the bottom thereof.

70. 7. In a portable camp stove, in combination, a casing adapted to receive a fuel tank having a generator tube attached thereto, the tank being within the casing and the generator tube on the outside thereof, said casing having a bottom, two side walls and two end walls, a support pivotally connected to the sides of the casing near one end thereof, said support having a straight portion adapted to be swung about the pivots into contact with the bottom or the end, a cover pivotally connected to the straight portion, said cover having a portion of curved cross-section with a straight flange secured along one edge, said cover being adapted to be moved into operative position against the end with the concave portion innermost, whereby a housing is formed for enclosing the generator tube, and means cooperating with the flange for holding the parts in operative position.

75. 8. In testimony whereof we affix our signatures.
